UNITED STATES PATENT OFFICE.

PETER L. WILBUR, OF TUCKAHOE, NEW YORK.

PUMPING MECHANISM.

Application filed December 16, 1921. Serial No. 522,730.

To all whom it may concern:

Be it known that I, PETER L. WILBUR, a citizen of the United States, and a resident of Tuckahoe, in the county of Westchester and State of New York, have invented certain new and useful Improvements in Pumping Mechanism, of which the following is a specification.

This invention relates to pumps and particularly double acting reciprocable piston pumps, and it is the primary object of the invention to improve the general construction and arrangement of the parts to adapt the same to be connected to and combined with a liquid carrying container to discharge the liquid therefrom by the operation of the pump to be used as a sprayer or otherwise.

It is a further object of the invention in pumping mechanism of this character to arrange the same with a discharge nozzle and provide improved valve mechanism operable during the reciprocation of the piston to control the connection of the nozzle with the pump cylinder at opposite sides of the piston.

It is another object of the invention to provide improved means to shut off the pumping mechanism and disconnect the liquid carrying container from the nozzle when the mechanism is not in use.

In the drawing accompanying and forming a part of this specification, Figure 1 is a perspective view of my improved pumping mechanism showing the same connected to a container for discharging the contents of the container.

Figure 2 is a side elevation of the pumping mechanism, partly in section, to illustrate the interior construction and arrangement thereof.

Figure 3 is a longitudinal sectional view of the discharge end of the pumping mechanism to show the manner of shutting off the pump from the discharge nozzle.

Figure 4 is a cross sectional view taken on the line 4—4 of Figure 2.

Figure 5 is a perspective view of the valve casing and plug for connecting the discharge nozzle with the pumping cylinder at opposite sides of the piston.

Figure 6 is a perspective view of a valve to operate in conjunction with the valve casing in Figure 5 to control the connection of the discharge nozzle with the pump cylinder at opposite sides of the piston.

Figure 7 is a view similar to Figure 3 showing modified means for shutting off the pump from the discharge nozzle.

Figure 8 is a view similar to Figure 7 but showing the parts in position with the discharge nozzle open to the pump.

Figure 9 is a perspective view of the valve mechanism disassembled for controlling the discharge of the liquid from the cylinder at opposite sides of the piston shown in Figures 7 and 8.

Figure 10 is a perspective view of the discharge nozzle.

Figure 11 is a perspective view, partly in section, and enlarged of the end of the piston cylinder to show the arrangement thereof for mounting therein the valve casing shown in Figures 5 and 9; and

Figure 12 is a view similar to Figure 3 showing a modified form of valve mechanism to control the discharge of the liquid from opposite ends of the pump and shut off the pump from the pump outlet.

Similar characters of reference designate like parts throughout the different views of the drawing.

In the drawing the improved pumping mechanism is mounted upon the exterior of a liquid carrying container C, shown as of circular form and substantially flat with the pumping mechanism mounted on one of the ends in communication with the interior of the container to discharge the contents of the container by the manipulation of the pump for use as a sprayer or the like. The embodiment of the mechanism illustrated comprises a cylinder 12 mounted at opposite ends in heads 13, 13', said heads being of semi-circular form with the flattened portion 14 (Figure 4) adapted to lie contiguous to the outer surface of the container when the pump is mounted upon the latter as shown in Figure 1. A nozzle 15 is secured in one end of the cylinder and a perforated plug 16 engages in the opposite end of the cylinder. A piston 17 arranged with suitable packing separates the cylinder into two chambers, the piston being reciprocated by a rod 18 fixed to the piston and extending through a stuffing box 19 arranged in the plug 16 and the perforation in said plug to the exterior of the cylinder and has mounted thereon an operating handle 20.

Inlet ports in the wall of the piston cylinder at opposite sides of the piston register with lateral ports in the heads 13, 13', as

shown at 21, 21', which ports communicate with openings 22 in said heads, tubes 23, 24 extending longitudinally of the piston cylinder being connected at one end with said 5 openings 22 and arranged at said ends with seats for suction valves 25, 25' shown of the ball type, to control the flow or entrance of liquid to the chambers at opposite sides of the piston during the reciprocation of the 10 piston. The opposite ends of the openings are closed by plugs 26 having a portion 27 of reduced cross sectional dimension at the inner ends of the plugs to extend into said openings for a purpose to be hereinafter described. The tubes 23, 24 through the openings 22 communicate with the chamber at the opposite sides of the piston through the ports 21, 21'. The opposite ends of the tubes are connected to a chamber in a casing 28 15 (Figures 2 and 4) located substantially midway between the ends of the cylinder and extending laterally to engage between the cylinder and container and having an inlet 29 (Figure 4) substantially at the axis of 20 the container for connection with the interior of the container centrally or axially thereof.

The discharge of the liquid from the chambers of the piston cylinder at opposite 30 sides of the piston is through a perforated plug 30 mounted in the cylinder between the nozzle and an inwardly extending annular bead 31 formed in the cylinder, said plug being arranged with a triangular 35 shaped recess 32 communicating with the nozzle orifice and having a port 33 axially of the cylinder through which to discharge the liquid from the chamber in front of the piston, said plug being arranged at the inner 40 end within the cylinder with a valve seat 34 for a purpose to be hereinafter described. To discharge the liquid from the chamber of the cylinder in back of the piston a lateral port 35 in the plug 30 registers with a 45 port 36 in the cylinder and a port 37 in the head 13', a tube or pipe 38 extending longitudinally of the piston cylinder being connected at one end to a port 39 in the head 13, said latter port registering with a port 40 in 50 the wall of the cylinder.

The plug 16 has a portion of reduced diameter within the cylinder to provide a passage for the entrance of liquid through the port 21 to the cylinder and the discharge 55 of the liquid through the port 40. The valve plug 30 at the nozzle end of the cylinder also has a longitudinal recess 41 in the outer wall in communication with the port 21' and cylinder for the entrance of the liquid through 60 port 21' to the cylinder chamber in front of the piston.

To control the ports 33 and 35, 36, 37 and the alternate discharge of the liquid from the cylinder chambers at opposite sides of 65 the piston, a valve 42 (Figure 6) of acute

triangular shape in longitudinal section and of less cross sectional area than the chamber 32 in the plug 30 is arranged in the plug chamber 32, as shown in Figure 2. As the piston is moved inward into the piston cylinder to discharge the liquid from the chamber in front of the piston through the axial port 33 the pressure of the liquid will move the valve 42 toward and hold it against the port 35, maintaining an opening through the 70 plug chamber 32 in communication with the plug port 33 and nozzle orifice, as shown in Figure 3. As the piston is moved outward and the liquid is discharged from the cylinder chamber in back of the piston the entrance of the liquid through the cylinder port 35 into the plug chamber 32 will seat and hold the valve 42 in position to close the axial port 33 and shut off said port from the nozzle orifice and maintain an open passage 75 between the port 35 and nozzle orifice through the chamber 32 by a recessed portion 42" in the valve 42 as shown in Figure 2, the valve and chamber being arranged and constructed so that the valve will oscillate or rock on the apex thereof, as shown at 32' in Figure 2.

As the liquid is discharged from in front of the piston any liquid passing through the plug recess 41 and cylinder inlet port 21' 95 will be caused to impinge against the rear side of the valve 25' due to the closure plug projection 27 extending to or beyond the axis of the port 21' and seat the valve upon the valve seat at the end of the tube 24.

During this movement of the piston suction at the back of the piston will unseat the valve 25 from the seat of tube 23 and draw liquid through said tube and port 21 into the chamber at the rear of the piston. During the reverse movement of the piston the valve 25 will be seated and the valve 25' unseated.

The chamber of the casing 28 and thereby the pumping mechanism is connected with 110 the interior of the container C by a tubular extension 43 of a ball shaped member 44 passing to the interior of the container through an opening axially or centrally in the wall thereof and secured in the inlet to 115 the casing chamber 28.

To connect the pumping mechanism with the liquid in that portion of the container which is lowermost a tubular pick up comprising a tube 45 is connected at one end to the ball member 44 in fluid communication with the tubular portion 43 and to have universal movement, the opposite inlet end of the pick up extending to the side wall of the container. The pick up tube is connected to the ball member 44 by a coupling comprising a member 46 (Figure 4) in which the tube 45 is fixed and arranged with a socket portion 47 conforming to the shape of the ball member and mounted upon 120 125 130

said latter member by having threaded connection with a cup shaped member 48 loosely mounted on the tubular portion 43 of the ball member 44 between said member 5 and the wall of the container. Suitable packing of anti-friction material is interposed between the cupped member 48, socket portion of coupling member 46 and the ball member 44 as shown at 49 and 50.

- 10 To shut off the nozzle orifice from the pumping mechanism and thereby from the container to prevent leakage from the container and pump when not in use the piston is arranged to engage the seat 34 at the inner end of the valve plug 30 and a plunger 51 is carried at the inner end of the piston to pass through the axial port of the plug valve chamber to engage and hold the valve 42 against the port 35 to close the same, 15 said valve in the face adjacent the port 35 having an inset of suitable material, such as velumoid, to assure the sealing of the port and prevent adhesion of the valve to the wall of the chamber 32 due to the corrosive 20 action of the liquid in the pump or otherwise. The plunger 51 is slidably mounted in the piston. For this purpose the piston is constructed of a tube 52 of less diameter than the cylinder having the piston rod 25 secured in one end and an annular flange at the end of the connection with the piston rod. A perforated cap 53 is threaded to the opposite end of the tube to form a shoulder between which shoulder and the 30 tube flange the piston packing is clamped. The plunger 51 passes through the cap perforation and has an annular shoulder within the piston with an extended portion to slidably engage in an opening in the end of the piston rod with a spring 56 coiled about 35 said plunger extension and confined between the end of the piston rod and the plunger flange to urge the plunger outward with the plunger flange in engagement with the cap 40 53. A perforate disk 57 of suitable material, such as velumoid, is carried at the end of the piston cap to engage the seat 34 of the valve plug 30 to assure the sealing of said port. It will thus be obvious that when 45 the piston is moved to its innermost position the disk 57 carried at the end of the piston will bear against the seat 34 and the piston plunger 51 will yieldingly engage the valve 42 though firmly seating the same to 50 seal the port 35.

The piston is retained in its innermost sealing position by cam projections 58 extending laterally from the handle which are adapted to pass through recesses 59 in 55 the wall of an inwardly extending annular flange of a tubular portion of the head 13 extending longitudinally of the piston rod, and the engagement of said cam projection below the flanged portion of the tubular 60 projection.

To permit of the entrance of air to the container C to displace the liquid as it is discharged therefrom by the pumping mechanism the stuffing box carrying plug 16 is arranged with a portion of reduced diameter 70 between the threaded portion of the plug and an annular flange 60 of the plug engaging at the outer end of the head 13 thereby forming an annular recess or chamber 61 between the plug and head with 75 which a port 72 open to the atmosphere communicates. The chamber 61 is in communication with the interior of the container C through a port in the head 13 and a tube engaging in said port and extending 80 into the container, as shown at 73 in Figures 1 and 2. To seal this air inlet port when the device is not in use and prevent the leakage of the liquid therethrough, a 85 suitable packing material, such as cork, velumoid, or the like 62 is seated in the annular recess of the operating handle at the connection of the piston rod therewith, said material seating against an annular seat 63 at the outer end of the plug 16 when the piston is locked in its innermost position and sealing the outlet ports 33, 35. This packing 62 also serves to seal the piston rod 90 when the device is not in use.

In Figures 7, 8 and 9 there is shown a 95 modified form of the valve shown in Figure 2. In this structure the recess 32 in the plug is of triangular form but is not cut through the opposite sides of the plug, (Figure 9), with the ports 33 and 35 communicating therewith, this plug being conveniently formed with the recess and ports by die casting. The valve 42 for controlling the ports 33, 35 is in the form of a flap valve consisting of a plate 65 pivotally 100 mounted in the plug recess to have movement toward and away from the ports 33, 35 by pins 66 engaging in perforations in the plug and in opposite recesses 67 in the valve. To shut off the interior of the pumping mechanism from the nozzle orifice with this construction of valve the plunger 51 carried by the piston passes through the port 33 of the plug with the end to seat in and close the nozzle orifice the nozzle having an 105 inset of suitable material having a perforation in line with the nozzle orifice, as shown at 68, to facilitate the sealing of the nozzle orifice.

In Figure 12 I have shown a further 110 modified construction and arrangement of valve mechanism to control the connecting of the piston cylinder at opposite sides of the piston with the nozzle orifice and control the discharge of the liquid from opposite sides of the piston as well as to shut off the pumping mechanism from the nozzle orifice. A plug 30' is arranged in the piston cylinder within the nozzle, said plug 115 having a port extending therethrough, the 120

same being of reduced diameter at the inner end to constitute the outlet port 33 of the piston chamber in front of the piston. The outer end of the bore of the plug is 5 closed by a block 33' forming a chamber within the plug with which port 33 communicates and connected with the cylinder port 36 through a longitudinal recess 31' in the outer surface of the plug 30' which 10 is also in communication with the chamber in the plug through the port in the block 33', as shown at 35'. The chamber within the plug is connected with the nozzle orifice through a port 70 having an opening 71 in 15 the plug chamber. The ports 33 and 35' are controlled by a valve in the form of a disk 42' slidably mounted to have longitudinal movement in the plug chamber. When the liquid is being discharged from the rear of 20 the piston the valve assumes the position shown in Figure 12 opening the port 35' to the opening 71 of port 70, and when the piston is moved inward to discharge the liquid from in front thereof the valve 42' is seated 25 against an annular seat 75 closing port 35' and opening port 33 to the port 71. To shut off the pumping mechanism from the nozzle outlet the piston is arranged with the spring influenced plunger 51 as hereinbefore described, the piston also being provided with a sealing disk 57 to seat against the annular seat 34 at the inner end of the plug to seal 30 the port 33 when the piston is in its innermost position. When the piston is in this 35 latter position the plunger passes through the port 33 moving the valve and holding it against the valve seat 75 to close the port 35', the face of the valve adjacent the port 35' having an inset of suitable material, such as 40 velumoid to seal the port and also preventing sticking of the valve by corrosion or otherwise.

Having thus described my invention I claim:

- 45 1. In pumping mechanism, a cylinder having a discharge nozzle; a piston reciprocable in said cylinder; valve controlled inlet ports to the cylinder at opposite sides of the piston; outlet ports connected to the nozzle and communicating with the cylinder at opposite sides of the piston; a valve to control the opening and closing of said outlet ports, said piston being arranged to seat said valve to close one of the ports and 50 to close the other port when the piston is in its innermost position to shut off the interior of the pumping mechanism from the atmosphere through the discharge nozzle.
- 55 2. In pumping mechanism, a cylinder having a discharge nozzle; a piston to reciprocate in the cylinder; valve controlled ports to the cylinder at opposite sides of the piston; outlet ports connected to the nozzle and communicating with the cylinder

at opposite sides of the piston; and a valve to control the opening and closing of said outlet ports, said piston being arranged to co-operate with said valve to maintain the outlet ports closed when in its innermost 70 position.

3. In pumping mechanism, a cylinder having a discharge nozzle; a piston to reciprocate in the cylinder; valve controlled ports to the cylinder at opposite sides of the piston; ports connected to the nozzle and communicating with the cylinder at opposite sides of the piston; and a valve to control the opening and closing of said latter ports; said piston being arranged to close one of the outlet ports and carrying means to co-operate with the valve to close the other outlet port when the piston is in its innermost position.

4. In pumping mechanism, a cylinder having a discharge nozzle; a piston to reciprocate in the cylinder; valve controlled inlet ports to the cylinder at opposite sides of the piston; an outlet port axially of the cylinder to connect the cylinder at one side of the piston with the nozzle orifice; an outlet port in communication with the nozzle orifice connected to the cylinder at the opposite side of the piston; and a valve to control the opening and closing of said outlet ports; said piston being arranged to close the axial outlet port and carrying means to seat the outlet valve against and close the other outlet port when the piston is in its innermost position.

5. In pumping mechanism, a cylinder having a discharge nozzle; a piston to reciprocate in the cylinder; valve controlled inlet ports to the cylinder at opposite sides of the piston; an outlet port axially of the cylinder to connect the cylinder at one side of the piston with the nozzle orifice; an outlet port in communication with the nozzle orifice connected to the cylinder at the opposite side of the piston; a valve between said ports operable to control the opening and closing thereof; means to close the axial port when the piston is in its innermost position; a plunger carried at the inner end of the piston to pass through the axial port and seat the outlet control valve against the other outlet port when the piston is in its innermost position; and means to releasably lock the piston in such position.

6. In pumping mechanism, a cylinder having a discharge nozzle; a piston to reciprocate in the cylinder; valve controlled inlet ports to the cylinder at opposite sides of the piston; a plug in the cylinder adjacent the discharge nozzle having a port axially of the cylinder in communication with the nozzle orifice to connect the cylinder in front of the piston with the nozzle orifice, and having a lateral port in communication with the nozzle orifice and connected to the cylinder

in back of the piston; and a valve in said plug operable during the reciprocation of the piston to control the opening and closing of the plug ports and the connection of the 5 cylinder at opposite sides of the piston with the nozzle orifice.

7. In pumping mechanism, a cylinder having a discharge nozzle; a piston to reciprocate in the cylinder; valve controlled inlet ports to the cylinder at opposite sides of the piston; a plug in the cylinder adjacent the discharge nozzle having a port axially of the cylinder in communication with the nozzle orifice to connect the cylinder in front of 10 the piston with the nozzle orifice, and having a lateral port in communication with the nozzle orifice and connected to the cylinder in back of the piston; a valve in said plug operable during the reciprocation of the 15 piston to control the opening and closing of the plug ports and the connection of the cylinder at opposite sides of the piston with the nozzle orifice; means carried by the piston to co-operate with said valve to seat 20 the same against and close the lateral plug port and to close the axial port when the piston is in its innermost position; and means to retain the piston in its innermost 25 position.
- 30 8. In pumping mechanism, a cylinder having a discharge nozzle and a stuffing box at the opposite end; a piston to reciprocate in the cylinder; valve controlled ports to the cylinder at opposite sides of the piston; an outlet port axially of the cylinder to connect the cylinder at one side of the piston with the nozzle orifice and arranged with a valve seat within the cylinder; an outlet port in communication with the nozzle orifice 35 connected to the cylinder at the opposite side of the piston; a valve between said ports to control the opening and closing of said outlet ports; means carried by the piston to co-operate with the valve seat of the axial outlet 40 port to close the same when the piston is in its innermost position; a plunger slidably mounted in the piston and normally urged outward therefrom to pass through the axial outlet port and engage the outlet valve to 45 seat the same against and close the other outlet port to the nozzle orifice when the piston is in its innermost position; and means to lock the piston of the pumping mechanism to releasably retain the piston in its innermost 50 position, and carrying means to seal the stuffing box when in such position.

9. The combination with a liquid carrying container, of pump mechanism mounted upon the exterior of the container comprising 55 a cylinder having a nozzle at one end, heads in which the cylinder is mounted at opposite ends, said heads having a portion to conform to and lie contiguous to the outer surface of the container and arranged with valve controlled inlet ports connected

to opposite ends of the cylinder; means to connect the inlet ports with the interior of the container; outlet means from the cylinder at opposite sides of the piston connected to the nozzle; valve mechanism to control 70 said outlet means to the nozzle; a piston to reciprocate in the cylinder; and means carried by the piston and co-operating with the outlet control valve mechanism when in its innermost position to shut off the 75 pumping mechanism and container from the discharge nozzle.

10. In pumping mechanism, a cylinder having a discharge nozzle at one end; a piston to reciprocate in the cylinder having an operating rod extending from the end of the cylinder opposite to the nozzle; valve controlled inlet ports to the cylinder at opposite sides of the piston; a plug in the cylinder adjacent the nozzle having a port axially of the cylinder in communication with the nozzle orifice to connect the cylinder in front of the piston with the nozzle; a lateral port in said plug in communication with the nozzle orifice connected to the cylinder at the rear side of the piston; a valve carried by said plug operable to control the connecting and disconnecting of said ports, and thereby the cylinder, at opposite sides of the piston with the nozzle 90 orifice; a plunger slidably carried in the inner end of the piston; a spring within the piston to urge the plunger outward from the piston; said plunger being adapted to pass through the axial port of the plug and 95 operable to seat the valve against the lateral plug port to close the same and the piston being adapted to be seated against and close the axial port when the piston is in its innermost position.

11. In pumping mechanism, a cylinder having a discharge nozzle at one end; a piston to reciprocate in the cylinder; valve controlled inlet ports to the cylinder at opposite sides of the piston; a plug in the cylinder adjacent the nozzle having a triangular recess in the end adjacent the nozzle and in communication therewith; and a port in said plug axially of the cylinder in communication with the plug recess to connect the cylinder in front of the piston with the nozzle; a lateral port from said plug recess connected to the cylinder at the rear side of the piston; a valve of acute triangular shape in cross section in the plug recess operable to control the connecting of the plug ports and thereby the cylinder at opposite sides of the piston with the nozzle orifice.

12. The combination with a liquid carrying container, of cylinder pumping mechanism including a cylinder in communication with the liquid in the container, a reciprocable piston, a piston rod and operating handle connected to the rod to discharge 125 130

the liquid from the container; a plug arranged in one end of the cylinder carrying a stuffing box in which the piston rod operates, said plug having an annular reduced portion to co-operate with the cylinder to provide an annular chamber, a port in the plug to connect said chamber with the atmosphere, a second port in the plug to connect the interior of the container with 10 said plug chamber, and means to seal the first named port in said chamber to the at-

mosphere when the piston is in its innermost position, comprising an annular seat arranged at the outer side of the plug, packing carried in an annual seat of the operating handle at the connection thereof with the piston rod to co-operate with said seat; and means to lock the rod in such position. 15

Signed at the city of New York, in the county of New York and State of New York December, 1921.

PETER L. WILBUR.
